UNITED STATES PATENT OFFICE.

CARL HERMAN BECK, OF SAN FRANCISCO, CALIFORNIA.

TIME-CONTROLLED ELECTRIC-SWITCH SYSTEM.

Application filed December 31, 1923. Serial No. 683,779.

To all whom it may concern:

Be it known that I, CARL HERMAN BECK, a citizen of the United States, and a resident of San Francisco, county of San Francisco, State of California, have invented a new and useful Time-Controlled Electric-Switch System, of which the following is a specification.

This invention relates to the time controlling, or predetermining, or periodic operation of electric circuits for any purpose whatever, either for direct operation of various electrically actuated devices or for the closing or opening of other and heavier circuits, valves, etc., for effecting the operation desired.

My invention is applicable for use in connection with any form of actuating mechanism having a direct or proportional movement with the hourly division of time and principally in association with a clock dial, preferably on the face thereof or in connection with other time mechanisms either mechanically or electrically driven or controlled by a central or master clock mechanism.

The principal objects of my invention are to effect a system of electrical switch control which will be exceedingly elastic in its application to industrial or scientific requirements, one in which a great variety of control can be secured with comparatively simple control units and which may be combined to secure the more complex controls necessary in order to carry out certain predetermined orders of mechanical or electrical functioning.

I realize the objects outlined in the system and apparatus illustrated in the drawings, and in which Figure 1 is a diagrammatic drawing showing a connected series of horological devices having various speed relations to any desired time unit, and a plurality of the devices equipped with the different modifications of my circuit controlling mechanisms.

Figure 2 is an enlarged plan view of one of the devices showing a plurality of my contact rings cooperating with two rotating arms.

Figure 3 is an enlarged sectional elevation of the rings, arms and contacting devices; and Figure 4 is a still larger sectional perspective view of a portion of the double or stepped ring of Figure 3.

Figures 5 and 6 are modifications in the

interchangeable contacting terminals; and Figure 7 shows a variation in the means for positioning the terminals.

Figures 8 and 9 are schematic views showing the application of my controlled circuits for stopping or starting a device.

Figures 10 and 11 show two of any number of circuit diagrams possible to employ with any set of contact rings.

Before going into constructional detail it might be stated that my invention is not limited to any fixed relation or number of elements shown in the drawing or arrangements of circuits employed with them, as any number of variations are possible and will be apparent to a person skilled in the art.

In Figure 1 the diagram represents a series of clock mechanisms or dials (1), (2), (3), (4), and (5), any one of which may be considered as the master device or clock, in this case assumed to be the central one (1)—and each dial having one or more arms or revolving hands as indicated, and the master clock a pendulum.

The mechanism of the master clock may be either a spring or weight operated device, or electro-magnetically controlled by another remote clock as may be desired, but since the clock mechanism per se forms no part of my invention it is not detailed in the drawings, but only the necessary functioning elements to illustrate the invention are shown, such as the main gears, arms, contact rings, terminals, etc.

The various overlapping dotted circles denoting gears are in different planes so as to avoid mechanical interference and all marked "h" correspond to what ordinarily operate the hour hands in clocks making one revolution every twelve hours, those marked "m" to the minute hand gears and those marked "s" to the second hand gears.

Any number of operative dials may be projected from the master dial by the use of intermediate gear wheels as shown, either to obtain a working dial having a second, minute, or hour hand only, or having both a minute and hour hand as indicated in the two dials to the right. Also, the direction of revolution is optional, depending on the number of intermediate gears.

The heavy circles on each dial represent my contact rings and upon or through any one or combination of which the circuits are completed or broken by the revolution or

spaced relation of the arms cooperating with various contacting devices.

The arms are marked S, M or H on the various dials to designate second, minute or hour as the case may be; and at (6) is indicated a device actuated by a circuit controlled from any of the dials for throwing the dial (5) into or out of operative relation with the others.

10 Figure 2 shows in enlarged plan the lower right hand dial and the contact rings, (15), (16), (17) and (18). These rings would be ordinarily below the arms or hands H, M as indicated and better shown in Figure 3 and 15 they are adapted to receive various electrical contacting terminals as shown in Figures 5 and 6 at (7) and (8) or in Figure 3 at (9) and which figure also shows contacts (7) and (8).

20 To receive any of these contacts the rings are provided with proper spaced holes (10) into which they may be inserted, and the arms or hands H, M are provided at the ends or other desired position with more or less 25 resilient wipers (11) for wiping over the terminals, also, on either or both arms a flange (12) for making other contacts.

The terminal (8) shows a flat resilient contacting element (8') projecting from it 30 and of course may be positioned in a hole to take advantage of this resiliency or placed in the opposite plane.

The duration of an electrical contact depends on the length of the resilient contacting member and is repeated upon each revolution of the arm which makes it, whereas 35 terminal (7) has a pivoted upper portion (7') which if presented in the proper position is turned down by the moving hand in 40 closing the contact and remains down, thus making but a single contact without repetition.

Contact (9) has a similar function to terminal (7) but provides for a long contact 45 even without a resilient member, and operates as shown in Figure 3, being pivoted from a counterbalancing lever (13) fulcrumed by hooking over a wire or pin (14) in one of any number of slots in the edge 50 of ring (15), and having its lower end bent outwardly to engage any of the holes (19) or (20) in the stepped ring (16). If engaged with holes (19) it becomes the stationary element of a wiping contact from the resilient 55 wipers (11), but if placed in a hole (20) which is slotted over a vertical opening (21), the wiper first makes an electrical contact then moves the device bodily to the end of the slot, at which time the counterweighted 60 arm (13) lifts the terminal (9) entirely clear of the arm M.

The terminal (9) may be used with the hour arm H by simply having the hour arm the longest of the two and preferably in the 65 upper position.

In practice there will be considerable variation in arranging the rings and the terminal receiving holes, etc. In the first place, the rings may be metallic or nonmetallic; if metallic they may be insulated or not, or the 70 holes may be metal bushed in insulating rings and provide for hundreds of separate circuits, the arms may be insulated and leading from separate circuits or not, or the entire operative mechanism may be the ground 75 or common return for one or any number of circuits.

If the rings are insulated a single arm may throw them into electrical contact, or different sets of rings, as there may be any 80 number of rings. Also one arm may be making a long wiping contact while the other is making short intermittent contacts so that an unlimited number of combinations can 85 be produced.

Instead of placing contact terminals of the type (7) or (8) into the holes (10) by hand, a series of levers might be arranged around the dials for simple pressing upon to project a terminal contact out of the ring 90 from below, as indicated in Figure 7 wherein the necessary elements are shown in association with one terminal to make such an arrangement operative,—the lever (22) being pivoted to the dial at (23) and having a finger key (24), with the other end connected to or arranged for lifting a terminal (8) to project above the ring (17) or (18). At (25) is indicated a suitable friction stop 95 or lock for holding the lever at either extreme position.

The controlled circuits provided by my system may be used to accomplish any desired mechanical or electrical result, and Figures 8 and 9 illustrate my method of stopping and starting a device, either a machine or a similar horological mechanism having a pendulum (26) swinging normally to the maximum position shown in Figure 8. Upon energizing the electro-magnet (27) 100 through one of the control circuits, the pendulum rod made of iron will be drawn beyond its maximum travel and locked by a snap pawl (28) shown in Figure 9 so that it cannot return after breaking the circuit. 110

This latter Figure 9 is an enlarged section of a portion of Figure 8 taken along the line 9—9 and shows the pendulum rod (26) locked by the pawl, pulled into the path 120 of the rod by the other end of the magnet (27).

To release the pendulum and start the device a second controlled circuit is closed through the electro-magnet (29) which will attract the armature (30) on the pivoted release rod (31) and thus throw the pawl. The release rod is held at either point by suitable resilient or frictional means as indicated at (32).

In Figures 10 and 11 illustrative circuit 130

arrangements controlled by my invention are shown, the former being the arrangement as suited for a hotel or call alarm system. In this example the inner ring would 5 be made of insulating material and the holes bushed with a conductor into which the contact terminals (7) would be placed, each bushing being connected to a pin jack (33). Pin jacks (34) lead to the telephone or call 10 bells in the various rooms. Pin jacks (35) are used when more than one room is to receive a call at the same time. Modern pin-jack switchboards could be used employing either metallic or ground return circuits.

15 In using pin-jack (36) the sides are connected to the rings and if conductor terminals are set in the rings the circuit would be completed through (36) at the intervals of time determined by the setting. When so 20 used it is of course necessary to have both rings of conducting material, and insulated from one another as well as from the hands. No circuit is established until both hands are in contact with their respective rings 25 through the terminals set in the rings at the desired time position.

In regard to the diagram shown in Figure 11, this shows the arrangement for causing a machine such as (37) to function for 30 a definite time periodically and is easily understood by any electrician. The circuit established by the hour hand on the inner ring serving to energize the coil of the machine (37) through the contacts of the locking relay (38), and when the minute hand makes a contact on the outer ring the clear-out relay (39) breaks the circuit and re-establishes the original condition with the machine at rest.

40 In considering my invention it will be seen that the system embraces a series of variously timed elements for making or breaking any combination of electrical contacts. The operations may be predetermined many 45 hours, or minutes, or reduced to second intervals by use of the various, or combinations of the various S, M or H arms. Also, for split second contacts further dials having higher speed value can be projected from 50 any of the dials in accordance with Figure 1. Also, the pendulum, (if used) of the master clock shown at (1') in Figure 1, being part of the cooperating horological set, may be conveniently used for split second 55 operations by providing it with a wiper (11') and adjustable contacts (40)—(42) at the ends of a ring section (41), the latter being the equivalent of one of the contact rings (17) or (18) and adapted for various 60 positioning of either terminals (7) or (8) as indicated, and for operation by the passing pendulum in the same manner as by the rotating arms.

Having thus described my invention and 65 illustrated its practical application, it will

be seen to be one admitting of considerable modification. The principal feature is of course the arrangement of contacts, the multiple rings and revolving arms; but whether the rings are stationary or whether they 70 revolve and the arms are stationary—or whether the rings are partially revolvable, etc., does not pass without the spirit of the invention, and any such modifications are intended to be covered in my appended 75 claims.

I claim:

1. In combination with a horological mechanism having a constantly rotating element, an electric circuit associated therewith 80 and means actuated by the rotating element for temporarily closing the circuit upon a rotation of the element through the element and of being inactive upon further rotations.

2. In combination with a horological 85 mechanism having a constantly rotating element, an electric circuit associated therewith and means actuated by the rotating element for closing the circuit upon a rotation of the element, said means presenting an active or inactive condition to a further rotation of the element depending on its initial setting.

3. In combination with a horological mechanism having a rotating element, an 95 electrical contact terminal adapted to be temporarily engaged for electrical contact by the rotating element and rendered inactive for further electrical contact by the movement of the element.

4. In combination with a horological mechanism having a rotating element, an electrical contact terminal adapted to be engaged by the rotating element, said element having a pivoted contact portion 105 adapted to be swung out of the path of travel of the element and beyond the point of any further contact therewith upon being moved by the element.

5. In combination with a horological 110 mechanism having a rotating element, an electrical contact terminal adapted to be engaged by the rotating element for making an electrical contact therewith, said terminal having a pivoted contact portion adapted to be swung out of the path of travel of the element upon being moved by the element, and means for swinging it entirely 115 clear of the path of travel to positively avoid further contact with the element upon its 120 next rotation.

6. In combination with a horological mechanism having a rotating element, an electrical contact terminal adapted to be engaged by the rotating element, said element having a pivoted contact portion adapted to be swung out of the path of travel of the element upon being moved by the element, and a counterweight for swinging it 125 clear of the path of travel.

7. In combination with a horological mechanism having a rotating element, an electrical contact terminal adapted to be engaged by the rotating element, and a stepped ring surrounding the rotating element, having means in both steps for selectively positioning said terminal therearound, the means in one step affording a fixed hold of the terminal for successive contacting, and in another step a tripping hold for release of the terminal after contacting.

8. In combination with a clock dial having a pair of rotating hands, a plurality of concentric rings on the dial under the hands adapted for the positioning therein of a plurality of electrical contact devices for selective engagement with the hands, one of the rings presenting the devices for successive contacting and another for nonsuccessive contacting.

9. Means for controlling a plurality of circuits comprising a clock dial with a pair of rotating hands thereover, means over

which the hands rotate for establishing an electric circuit at a predetermined time, said means being actuated by engagement with a rotating hand or hands, and similarly positioned means actuated by a hand or hands for breaking the circuit at a predetermined time interval.

10. Means for controlling a plurality of electrical circuits for starting and stopping a machine comprising a clock dial with a pair of rotating hands thereover adapted to establish short period electrical circuits at spaced predetermined time intervals, a swinging member on the machine having a normal path of travel, an electro-magnet energized by one of the circuits for drawing the swinging member beyond its normal path, a locking device for retaining the swinging member in such position, and an electromagnet energized by a later controlled circuit for releasing the locking device.

CARL HERMAN BECK.
